QUICK RELEASE AERIAL DELIVERY UNIT

Paul F. Helmick, Dayton, Ohio

Application January 8, 1942, Serial No. 426,035

4 Claims. (CL. 244—138)

(Granted under the act of March 3, 1883, as
amended April 30, 1928; 370 O. G. 757)

The invention described herein may be manufactured and used by or for Government for governmental purposes, without the payment to me of any royalty thereon.

This invention relates to improvements in aerial delivery apparatus and particularly to containers for use in conjunction with parachutes for dropping articles of a breakable nature from aircraft to the ground, the embodiment herein shown being particularly adapted for dropping rifles, machine guns or other equipment safely.

An object of the invention is to provide a device of this kind which may be quickly opened upon landing.

Another object is to provide a device of this character which will so hold the articles being dropped as to insure against breakage.

Another object is to so construct the several parts of the device that it will be durable and able to withstand the severe usage to which a device of this character is subjected.

Another object is to so arrange the container and the parachute with respect to each other as to insure safety in operation at all times.

Other objects and meritorious features will become evident as the invention is described in greater detail and reference is had to the drawing, wherein,

Fig. 1 is a perspective view of the improved device assembled ready to be dropped from some form of aircraft.

Fig. 2 shows one of the members of the assembly Fig. 1 in detail perspective.

Like reference numerals refer to like parts throughout the drawing.

The embodiment of the invention herein shown and described comprises a middle section 10 with two telescoping end caps 12 and 14 and a parachute pack 16 attached to one of the end caps.

The middle section 10 is shown as being of prismatic form, although it may be made cylindrical if so desired. It may be made in the form of an open ended box into which a number of suitably padded articles such as machine guns or rifles may be inserted, or it may be made in the form of a long blanket or rug which is rolled around the articles to be dropped, or between the turns of which the articles are spaced apart. The length of the middle section 10 may vary according to the length of the articles which it contains.

The end cap 12 which slips over one end of the middle section 10 may be made in the form of a box with one end open. The cap 12 may be made of duck or other suitable fabric, the length of the cap preferably being about one third the

length of the middle section 10. For use with a round or roll type middle section 10, the end cap will, of course, be made in the form of the drum with one end open.

5 A reinforcing band 18, composed of one or more layers of cotton webbing, surrounds the open end of the end cap 12, and is preferably stitched to the cap for the greater part of the way around it, an unstitched portion 20 being provided midway of its length with a buckle 22 which may be used for taking up the open end of the cap somewhat when the middle section is not large enough to quite fill the end cap.

15 A reinforcing strap 24 extends over the closed end of cap 12, then axially along opposite sides of the cap to the band 18. The strap 24 is preferably stitched to the sides and bottom of the cap 12, the ends terminating at the band 18 and being stitched thereto as at 26.

20 A second reinforcing strap 28 extends over the closed end of the cap 12 crosswise of the strap 24, an additional piece being looped out as at 30 to provide a hand grip to facilitate lifting the device when necessary. After crossing the end, 25 the strap 28 extends axially along opposite sides of the cap to and beyond the band 18, the strap being stitched to the cap and to the band where it crosses it. The free ends of the strap 28 are prolonged considerably beyond the open end of the cap, one of the ends being provided with one member 32 and the other end with the opposite member 34 of a quick release fastener 35, and a buckle 36 for adjusting the length between the two caps 12 and 14.

30 35 The end cap 14 which slips over the other end of the middle section 10 is exactly like the cap 12 above described except that it is provided at the closed end with eyelets 38 through which a break thread 40 is passed in lacing the cover 42 of the parachute pack 16 to the end cap 14.

40 45 Chute risers 44 are secured by appropriate fasteners 46 to rings 48 through which both the bands 18 and straps 28 pass. Risers 44 enter the pack 16 where the cover 42 is joined to the cap 14 by the break thread lacing 40 and are joined in the usual manner to the shroud lines of the parachute canopy 50, the top center of the canopy in turn being attached by a light break cord to a static line 52 which may emerge from the pack at the lacing and operate in the usual manner.

50 55 In operation the rifles, machine guns, or other pieces of equipment which are to be dropped, are carefully packed in the middle section 10, the ends caps 12 and 14 are slipped over the ends

of the package, the parachute pack 16 having previously been made up and laced to the end cap 14, and the two parts 32 and 34 of the quick release fasteners 35 are joined together. If the end caps are not drawn together closely to the ends of the package, the buckles 36 may be adjusted to shorten the free ends of the straps 28. If the cross-section of the package is slightly smaller than will fill the end caps, the buckles 22 may be slightly adjusted. The risers 44 are now attached to the rings 48 by fasteners 46, the static line 52 is properly fastened to the plane, and the device is ready to be dropped.

When the container lands, only two quick release connections 35 need be undone in order to pull off the end caps 12 and 14, after which the articles in the middle section 10 may be withdrawn therefrom, either from the end or by unrolling as the case may require.

The advantages of the device are obvious. It provides a means of opening the container and removing the articles in a minimum of time and is adjustable in length and in cross-section to fit packages of varying dimensions.

Having described my invention, I claim:

1. In an apparatus of the character described, a middle section adapted for holding articles to be dropped in padded spaced apart relation, a pair of end caps of fabric, each having one end

open, said open ends being slidable over the ends of said middle section, a reinforcing band surrounding the open end of each cap, said band being stitched to the cap except for small portions near the ends which are unstitched, an adjusting buckle secured to the unstitched ends, a reinforcing strap stitched across the closed end of each cap, then lengthwise across opposite sides and to the band, a second reinforcing strap stitched across the closed end crosswise of the first, then lengthwise across opposite sides to and beyond the band, separable parts of a quick release fastener and buckles for adjusting the length of said second strap carried by the outer ends of the portions which extend beyond the band, and means on the bands for attaching parachute risers.

2. The device defined in claim 1, wherein the means for attaching parachute risers comprises a ring on each end cap surrounding both the band and the second said strap, and a spring snap on each riser for attachment to said rings.

3. The device defined in claim 1 with means on one of the end caps for a lacing for securing the cover of a parachute pack.

4. The device defined in claim 1 in combination with a parachute pack secured to one of the end caps by a lacing of break thread.

PAUL F. HELMICK.
